UNITED STATES PATENT OFFICE.

GEORGE H. NOBBS, OF WATERTOWN, MASSACHUSETTS.

APPARATUS FOR CLEANING AIR.

Application filed January 18, 1921. Serial No. 438,228.

To all whom it may concern:

Be it known that I, GEORGE H. NOBBS, a citizen of the United States, residing at Watertown, in the county of Middlesex and State of Massachusetts, have invented certain new and useful Improvements in Apparatus for Cleaning Air, of which the following is a specification.

This invention relates to improvements in an apparatus for cleaning air; more particularly for freeing air from dust, grit and floating particles. It is herein illustrated as it has been developed for the intake of an internal combustion engine. Such engines suffer greatly when used in regions where the air carries dust, as for example when used in tractors and automobiles on dusty roads or fields, in which case gritty particles carried in with the air grind away the cylinder and piston, obstruct the valves and by working into the oil wear out the principal bearings. Efforts to clear this air have always heretofore, so far as I am aware, been in the direction of straining operations, or else of passing the air through a liquid. But the former retard the inflow of air to the engine, preventing it from getting its needed charge, and become additionally obstructive by becoming clogged in proportion as they are effective in stopping dirt; and the latter are both impractical under ordinary working conditions and are ineffective because of dust being carried along in the midst whenever any considerable body of air goes through the liquid. The present invention, seeks to avoid these evils, and provides so that neither air nor dust have to pass through any obstructing medium (either in the nature of a screen or a liquid) in order to become separated from each other. The separation is effected by causing the air to pass through a series of sharp deflections of direction, at each of which all solid particles carried by it tend to continue in their original direction; and more or less of them strike the deflecting wall, said wall being preferably soft and hairy, as when covered with felt, and being oily, the particles which strike it adhere to it. Thus the air is gradually cleared. The dust which has struck the wall becomes covered with a film of oil which spreads over it from the adjacent surface, and makes that dust help in catching other dust that strikes on top of it. Having lost momentum, and being constantly drawn by gravity,

all particles which do not adhere securely tend to slip down to the foot of the wall. The supply of oil on the wall, to catch and to cover the arriving particles, is maintained by capillary attraction from a body of liquid at the foot of the wall. The dust entrapping liquid is not necessarily oil, but when used in connection with an engine is preferably something not much affected by several hundred degrees of temperature. For this purpose oil of a heavy kind, such as is commonly used in lubricating gas engine cylinders is both convenient and effective. The entrapping walls are arranged in a receptacle, which may conveniently be cylindrical, with entrance at perimeter, discharge at axis, and connecting passage extending around the axis in a wavy line, the passage being so ample as not to be affected by accumulation of dust on its walls or bottom. It may moreover be arranged for easy cleaning, replacement of capillary material on the walls, or for supply of oil by squirting from any ordinary oil can, or by pouring from some other container. The apparatus and materials may be varied in form and substance; and may be applied to various other uses than those particularly above mentioned. It is intended that the patent shall cover by suitable expression in the appended claims whatever features of patentable novelty exist in the invention disclosed.

In the accompanying drawings:

Figure 1 is an elevation in section on line 1—1 of Figure 3, showing a preferred style of apparatus for practising the process of the invention;

Figure 2 is an elevation showing the intake openings thereof;

Figure 3 is a plan in section on line 3—3 of Figure 1;

Figure 4 is a medial section showing another form of apparatus;

Figure 5 shows the cover of Figure 4; and

Figure 6 is a plan in section showing another form of apparatus by which the invention may be practiced.

The apparatus illustrated in Figures 1, 2, 105 and 3 of the drawings comprises a receptacle whose cylindrical shell 10 forms an annular chamber about an axial passage herein called the discharge pipe 12 extending out through the bottom 14. Air enters the chamber 110 through openings 16 in the shell, and traverses a tortuous path therein to the pipe

12 which may lead to the carburetor of an internal combustion engine. The entrance openings 16 are shown covered by a screen for preventing the ingress of large particles, but such screens should be large enough not to become clogged, and can be omitted if desired, as the process and apparatus of the invention will separate dust particles of any size without any screening or filtration.

10 The pipe 12 extends down from the top where it is closed by the cover 18 of the receptacle. The cover is secured in position by any suitable means such as bolts 20 and thumb nuts 22. The bottom 14 may be soldered tight to the shell and to the pipe, to prevent leakage of oil, in case oil is kept in the bottom as illustrated. It should be understood however that the liquid body can be omitted, and that the device can be used 20 any side up. The air passing through the chamber to the pipe is repeatedly turned from straight line flow by a succession of deflecting walls or partitions. Such a partition 24 extending from the shell to the pipe and from the bottom to the cover between the chamber entrance and the chamber outlet forces the air to move around the axial pipe. In so doing, the air encounters other deflecting walls or partitions, 26, 28, arranged in two series, in one of which the partitions 26 extend radially inward from the shell toward the pipe, and in the other of which the partitions 28 extend radially outward from the perimeter of the axial pipe toward 30 the shell. The members of one series alternate with those of the other in changing the direction of the air currents. These partitions run to top and bottom of the receptacle, but stop short of crossing the chamber fully to the pipe, or to the shell, respectively, thus leaving openings 30 at their free edges which are alternately near the axis and near the perimeter of the chamber. When the air has traversed this labyrinth and comes eventually to the other side of the partition 24 it is deflected thereby into an opening 32 in the discharge pipe and thence passes out.

50 Any solid particles moving with the air are subject to the law of nature that they severally tend to continue moving with unchanged direction. At every deflection, and especially at every abrupt change in the course of the air current, some of them will impinge against the surfaces of the deflecting elements. This absorbs their momentum. These surfaces are adhesive, being illustrated as faced with felt 34 attached by any suitable means, stitches 35 of wire being represented. The hairy felt deadens the tendency of hard particles to rebound into the moving current of air and there is a dust-trapping liquid such as oil 36 which may be squirted over it as from an oil can, and will be distributed automatically both

by the natural property of oil to diffuse itself, and by capillary attraction through the felt, or oil will thus be distributed from a quantity poured into the bottom of the chamber, if the receptacle is fixed upright 70 as shown in Figure 1.

In Figures 4 and 5, the series of deflecting partitions are concentrically arranged within the receptacle, one series in this embodiment being attached to the bottom and the other to the cover. The innermost wall, which is secured to the bottom, provides the exit from the cleaner, it being in the form of a tube 12 which may be slipped over or screwed to the apparatus or pipe into which 80 the air is to go next. Other cylindrical walls are attached to the bottom 14 concentrically about the axis of the shell, and extending nearly to the cover 18. Only one such wall is shown in the drawings. Similar partitions 40 are attached to the cover 18 so as to lie between the walls 38 extending from the bottom. The bottoms of the depending walls are notched to provide openings 42 for the passage of the air under each 90 at the bottom. The intervening walls from the bottom do not extend quite to the cover, thereby leaving an annular passage for air over each at the top. The several circular deflecting walls are covered with felt 34 or the like for the same purpose as heretofore described. In this design a supply of oil 36 may be retained in each section of the bottom; and this can feed the capillary material on both partitions, because those depending from the cover reach the very bottom between the air-pass notches. The air enters the openings 16' which are placed at intervals around the shell near the cone; strikes the first annular partition which 95 deflects it toward the bottom of the chamber; strikes the bottom, which deflects it to horizontal direction, passing through notches; strikes the first partition rising from the bottom, which deflects it to vertical direction; and so it goes on with successive 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 own tendency to continue moving in a straight line is subject to the strong probability that it will be caught in one of the later air deflections; and is liable also to be thrown against a wall by eddy currents. The free and open character of the passage through its course is to guarantee against clogging or closure of the passage by accumulations of dust when in use. It is desirable that the passages be small enough so that the air must flow at a good velocity through them when the device is in operation. Accumulations of dust may proceed to considerable size before cleaning is needed; and cleaning is easily effected upon removing the cover. If the liquid be oil, swishing a little gasoline will loosen the accumulations.

I claim as my invention:

- 20 1. An air cleaner, comprising an annular chamber with air opening near the axis and another near the perimeter, and containing a series of baffle plates arranged alternately extending inward from the perimeter wall and outward from the axial wall, whereby the current travels around the axis with repeated deflections of direction; and means to maintain a film of dust-catching liquid on the baffle plates.
- 25 2. An air cleaner, comprising means to form the air that is to be cleaned into a current; and an impenetrable wall set across the direction of flow, adapted to deflect the current of air; said wall having a fibrous surface holding by capillary attraction a dust-catching liquid film against which the current impinges.
- 30 3. An air cleaner, comprising means to form the air that is to be cleaned into a current; and an impenetrable wall set across the direction of flow, adapted to deflect the current of air; said wall having a felt surface holding non-evaporative oil.
- 35 4. An air cleaner, comprising a box closed on all sides, except for inlet and outlet of air; adapted to hold a body of dust-catching

liquid in its bottom; having baffle plates, rising therefrom, arranged to make a tortuous passage from inlet to outlet; and having on the baffle surfaces material with capillary passages for drawing up and holding the liquid in position to receive impact of solid particles thrown against the baffles by the currents.

5. An air cleaner, comprising a passage having a series of dust adhesive baffle plates; projecting from opposite walls of the passage, plates of one series being arranged in alternation with and overlapping plates of the other series so as to form a tortuous course for air.

6. An air cleaner, comprising a box having body and cover portions, baffle plates on each portion extending toward the other portion and overlapping the plates thereon, arranged to cooperate with the plates on the other in forming a continuous tortuous course for air through the box when the cover is on the box, and forming open compartments of double passage width in each when the cover is removed; said baffle plates having dust-adhesive surfaces.

7. An air cleaner, comprising a series of dust-adhesive air-deflecting plates, said plates being arranged around an axis to make a free tortuous course for air and having in high degree the special quality of being adhesive to dust and each being fixed at an abrupt angle with respect to the plates which immediately precede and follow it in the series.

8. In combination, means for establishing a current of air to be cleaned, a rigid wall having a felt surface holding oil non-evaporative at the normal temperature of use, said wall being set for said current to impinge thereon and being adapted to deflect said current.

Signed at Boston, Massachusetts, this tenth day of January, 1921.

GEORGE H. NOBBS.
